[57] **CLAIM**

The ornamental design for a water filtration pitcher with lid and cartridge receiving reservoir, as shown and described.

DESCRIPTION

FIG. 1 is a side view of the first embodiment of the invention;

FIG. 2 is a side view of the first embodiment of the invention;

FIG. 3 is a rear elevational view thereof;

FIG. 4 is a front elevational view thereof;

FIG. 5 is a top view of the first embodiment of the invention;

FIG. 6 is a bottom view of the first embodiment of the invention;

FIG. 7 is a perspective view of the first embodiment of the invention;

FIG. 8 is a side view of the second embodiment of the invention;

FIG. 9 is a side view of the second embodiment of the invention;

FIG. 10 is a front elevational view thereof;

FIG. 11 is a rear elevational view thereof;

FIG. 12 is a top view of the second embodiment of the invention;

FIG. 13 is a bottom view of the second embodiment of the invention; and,

FIG. 14 is a perspective of the second embodiment of the invention.
